Patented Nov. 30, 1915.

Inventor

JACOB SKLAR

By *Watson E. Coleman* Attorney

UNITED STATES PATENT OFFICE.

JACOB SKLAR, OF PHILADELPHIA, PENNSYLVANIA.

WAIST-CLOSURE.

1,162,260.

Specification of Letters Patent.

Patented Nov. 30, 1915.

Application filed November 16, 1914. Serial No. 872,420.

To all whom it may concern:

Be it known that I, JACOB SKLAR, a subject of the Czar of Russia, residing at Philadelphia, in the county of Philadelphia and State of Pennsylvania, have invented certain new and useful Improvements in Waist-Closures, of which the following is a specification, reference being had to the accompanying drawings.

10 This invention relates to garments, and has for its primary object to provide improved means embodied in the construction of trousers, skirts, and similar garments, whereby the same may be properly fitted and supported upon variously shaped figures.

20 The invention has for a more particular object to provide an improved waist band construction whereby the trousers, skirt, or other garment may contract or expand so that the same will fit snugly over the hips, and the use of belts, suspenders, or analogous supporting means thereby dispensed with.

25 The invention has for a further general object to provide an improved garment having the above noted structural characteristics which will greatly add to the neat appearance of the wearer, while at the same time, the cost of making such garment is not increased to an appreciable extent.

30 With the above and other objects in view, my invention consists in the novel features of construction, combination, and arrangement of parts to be hereinafter more fully described, claimed, and illustrated in the accompanying drawings, in which,

35 Figure 1 is a perspective view of the waist-band portion of a pair of trousers, illustrating the application of my invention thereto; Fig. 2 is a horizontal sectional view; Fig. 3 is an enlarged fragmentary elevation, showing the gap or vent in the hip portion of the waist-band; and Fig. 4 is a detail section taken on the line 4—4 of Fig. 1.

40 Referring in detail to the drawing, 5 designates a pair of trousers which are of the usual form, the upper front portion above the crotch having the separable edges 6 which are provided with suitable fasteners.

45 The numeral 8 designates what I shall hereinafter term as a constricting band, said band being provided for the purpose of holding the waist band of the trousers snugly over the hips of the wearer, but admitting of a certain amount of expansion so that the trousers may be properly fitted

upon persons of different waist measurements. This band includes two end sections 9 which are of canvas or other non-elastic material, a central section 10 also of canvas, and the side sections 11. These latter sections of the band are formed of rubber or other suitable elastic material and secured at their ends to the extremities of the respective end sections 9 and to the extremities of the central canvas section 10. The canvas sections 9 of the band are provided upon their other ends with suitable fastening elements 12 whereby they may be conveniently connected or disconnected.

50 Upon each side of the waist portion of the trousers where the same will extend over the hips of the wearer, the same is vertically cut to produce a vent or gap indicated at 13, the material at one side of this gap having an 70 extended tab or tongue 14 which is adapted to lap upon the inner face of the opposed side of the gap. The band 8 above referred to is disposed upon the interior of the waist band of the trousers and is held in place by 80 a suitable lining strip. This lining strip includes the front sections 15 which are sewed or otherwise secured at their longitudinal edges to the material at opposite sides of the front opening of the trousers, and a 85 back section 16 which extends around the rear portion of the waist band and terminates upon opposite sides thereof. These sections of the lining are connected at their opposed ends by spaced elastic straps 17, 90 said straps being secured to the outer sides of the lining sections 15 and to the inner sides of the section 16, but at some distance from the extremities of said latter section. It is, therefore, seen that in the normal condition of the trousers, the elastic straps 17 95 are almost completely covered or hidden by the ends of the lining section 16 which extends over the same. It is also to be noted that as the lining sections 15 and 16 are securely stitched to the front and rear portions of the trousers, said yieldably connected sections will prevent the flap 14 from becoming displaced, and thus obviate the 100 opening of the gap 13.

105 By the provision of the lining sections 15 and 16 attached at their longitudinal edges to the body of the trousers, a tunnel or channel is formed for the belt or band 8 which supports the band in position and practically hides the same entirely from view, but permits of its free sliding movement for the

proper adjustment of the trousers about the waist of the wearer.

From the foregoing description, taken in connection with the accompanying drawing, the construction, manner of operation, and several advantages of my improved garment will be clearly and fully understood. By the provision of the constricting means in the waist band, it will be manifest that the trousers will snugly fit around the waist, and it is not necessary to consider the particular waist measurement in the making of the garment. As the trousers by expanding in the waist portion, are applicable to various waist sizes within certain limits, the necessity of altering the garment in order to assure a perfect fit, is also avoided. When the trousers or other garment is in use, the holding means therefor is invisible. The gaps or vents 13 over the hips are also held against further opening movement, by the provision of the resiliently connected lining sections, and the expansible belt which, in turn, contracts said lining sections and holds the same snugly around the wearer's waist. It will be obvious that by eliminating the necessity of employing an exterior belt, suspenders or like supporting means for the garment, the neat appearance of the wearer as well as his comfort, is materially enhanced. In view of the comparatively simple construction employed, it will be understood that the invention can also be embodied in the garment construction at only a slight additional cost to that incurred in the practice of the methods now in general use.

While I have illustrated the invention in its application to a pair of trousers, it is to be borne in mind that the device is also designed for use in connection with ladies' skirts and all other garments of a like

character where the same are suspended from the waist. The invention is also susceptible of a great many minor modifications in the form, proportion, and arrangement of the several elements employed, and I, therefore, reserve the privilege of resorting to all such legitimate changes as may be fairly embodied within the spirit and scope of the appended claims.

Having thus fully described my invention, what I desire to claim and secure by Letters Patent is:—

1. A garment having a waist-band provided with gaps on opposite sides, flexible strips secured along their longitudinal edges to the inner face of the garment at the edge of the waist-band and providing a tunnel, elastic connections between the ends of said strips, and a constricting band to fasten the garment upon the body of the wearer slidably disposed through said tunnel.

2. A garment having a waist-band provided with vertical gaps in the hip portions thereof, lining strips secured along their longitudinal edges to the inner face of the garment at the edge of said hip portions, said strips having free end portions, elastic connections between the free ends of the strips normally acting to close said gaps, and a constricting band supported between the attached edges of said strips and the body of the garment and freely movable therebetween, whereby the waist-band may be adjusted and the garment secured upon the body of the wearer.

In testimony whereof I hereunto affix my signature in the presence of two witnesses.

JACOB SKLAR.
